DESIGN FOR AN ELECTRICAL CONNECTOR PLUG

Stanley Bindman, New York, N. Y., assignor to
Noma Electric Corporation, New York, N. Y., a
corporation of New York

Application April 22, 1946, Serial No. 128,866

Term of patent 14 years

(Cl. D26—1)

To all whom it may concern:

Be it known that I, Stanley Bindman, a citizen of the United States, residing at New York, Bronx County, and State of New York, have invented a new, original, and ornamental Design for an Electrical Connector Plug, of which the following is a specification, reference being had to the accompanying drawing, forming part thereof.

Fig. 1 is a front elevational view of an electrical connector plug embodying my new design;

Fig. 2 is a side elevational view of the same;

Fig. 3 is a bottom end view thereof, and

Fig. 4 is a top end view thereof.

The dominant features of my new design reside in the portions shown in full lines.

I claim:

The ornamental design for an electrical connector plug, substantially as shown and described.

STANLEY BINDMAN.
